UNITED STATES PATENT OFFICE.

CLAUDE MORRIS LOWE, LINCOLN ROSS LOWE, AND CECIL WAYNE LOWE, OF KANSAS CITY, MISSOURI.

FLOOR CONSTRUCTION.

Application filed April 16, 1924. Serial No. 706,967.

To all whom it may concern:

Be it known that we, CLAUDE MORRIS LOWE, LINCOLN ROSS LOWE, and CECIL WAYNE LOWE, citizens of the United States, residing at Kansas City, in the county of Jackson and State of Missouri, have invented new and useful Improvements in Floor Construction, of which the following is a specification.

10 This invention relates to improvements in a floor structure, the general object of the invention being to make the floor in sections so that it can be easily assembled and taken apart and one which will give a smooth even 15 surface when assembled and when in knocked down position will occupy the minimum amount of room.

The floor is especially adapted for use in amusement parks, fairs or any place where 20 a portable floor is required and speed in laying down and taking up is essential. The floor may be used for skating rinks, dance floors and other purposes.

Another object of the invention is to provide 25 cables for holding the sections in assembled position with means for tightening the cables by bolts.

This invention also consists in certain other features of construction and in the 30 combination and arrangement of the several parts, to be hereinafter fully described, illustrated in the accompanying drawings and specifically pointed out in the appended claim.

35 In describing the invention in detail, reference will be had to the accompanying drawings wherein like characters denote like or corresponding parts throughout the several views, and in which:

40 Figure 1 is a plan view of a floor constructed in accordance with this invention.

Figure 2 is a section on line 2—2 of Figure 1.

45 Figure 3 is a section on line 3—3 of Figure 1.

Figure 4 is a plan view showing a portion of one corner of the floor.

Figure 5 is a bottom plan view of one of the sections.

50 Figure 6 is a section on line 6—6 of Figure 5.

Figure 7 is a perspective view of a portion of the section adapted to be associated with the section as illustrated in Figure 5.

Figure 8 is a similar view of a section 55 showing the modified form of connecting means.

Figure 9 is a similar view of a portion of a section adapted to be associated with the section as shown in Figure 8. 60

Figures 10 and 11 are similar views showing the end connecting means for the section as shown in Figures 8 and 9.

As shown in these views, the floor is composed of a plurality of sections which are 65 numbered in Figure 1 from 1 to 64. Each section comprises the joists and the flooring 2 which is nailed or otherwise secured to the joists. This flooring has square ends and side edges so that one section will make 70 a tight joint with the adjacent sections and in some cases we lay the flooring in the log cabin or boxed end style, as shown at 3, though this is not absolutely necessary as it adds to the expense and in some cases it 75 is preferable to lay the flooring straight across the joists. In those sections in which the log cabin style of flooring is used we provide stringers 4 which are mortised into the joists, as shown at 5, to support the 80 transversely extending flooring as shown in Figures 5 and 6. Some of the sections have their joists formed with the projecting tongues 6 for engaging the recesses 7 in the ends of the joists of other sections, these 85 recesses and tongues being preferably of rounded formation. Other sections are provided with square tongues 8 at one end of 90 each joist for engaging the recesses 10 formed in the sides of the end joists of other sections. The joists of all the sections project at one side thereof, as shown at 11, and these projecting ends interlock with those of abutting sections when the sections 95 are arranged in staggered formation so as to prevent movement of the sections in relation to each other. Most of the sections are each provided with a groove 12 in one of its end joists with this joist extending beyond the ends of the flooring, as shown at 13, and the other end joist is provided with a tongue 14 for engaging the groove in the abutting section and the flooring projects 100 beyond this joist which carries the tongue 14, as shown at 15.

From this arrangement it will be seen that the sections interlock with each other so as to produce a strong and firm floor structure,

the parts of which are immovably held together and the joists of which make close contact.

The sections are connected together by the cables 16 which are fastened to the bolts 18 so that by tightening these bolts the cables will be tightened and thus the sections will be firmly bound together.

When shipping or storing the sections, 10 the joists of one section are placed between those of another section so that the sections will occupy the minimum amount of space.

The construction is very simple, the strain 15 is evenly divided and there is no chance of any of the sections becoming displaced or loosened. The floor can be laid on any smooth surface or it may be laid on a foundation formed of beams such as shown 20 at 19 in Figures 2 and 3. The aligned beams may be held together by the U-shaped clips 20 which engage holes in the abutting ends of the beams.

While the sections may be arranged in 25 various ways and different sizes of floors constructed from them, Figure 1 gives an example of the formation of a floor. As will be seen from this figure sections 1 to 8 are arranged in pairs side by side with 30 the sections 9 and 10 at the ends of the arranged pairs. Each pair of sections 1 to 8 have their abutting sides connected together by the tongues 6 engaging the recesses 7 and the sections of each end pair 35 are connected with each section 9 and 10 by the tongues 8 engaging the recesses 10. The sections 11, 15, 18 and 22 are each provided with tongues on the joists on the outer 40 half of the section at one side thereof for engaging the recesses formed in the end joists of the sections 9 and 10. In all the

other sections the projecting ends of the joists overlap and extend under the flooring to firmly interlock the sections together and these sections are also connected together at their ends by the long tongues and grooves formed in the joists at the ends of the sections. 45

Attention is called to the small loading or storage space required of this floor for 50 by turning or inverting every other section two sections will occupy the space of one except where the stringers are used for supporting the boxed floor, where a little more space is taken up owing to the 55 flooring of the two sections being spaced a slight distance apart by the engagement of the joists with these stringers.

It is thought from the foregoing description that the advantages and novel features 60 of the invention will be readily apparent.

We desire it to be understood that we may make changes in the construction and in the combination and arrangement of the 65 several parts, provided that such changes fall within the scope of the appended claim.

What we claim is:—

A floor structure of the class described comprising a plurality of sections, each consisting of a number of joists and flooring 70 connected with the same, some of the joists having tongues formed on the ends of the joists and other sections having recesses formed in the ends of the joists for receiving the tongues so that the sections can 75 be locked together.

In testimony whereof we affix our signatures.

LINCOLN ROSS LOWE.
CLAUDE M. LOWE.
CECIL W. LOWE.
